(57) CLAIM

I claim the ornamental design for a nail clipper case, as shown and described.

DESCRIPTION

FIG. 1 is a front, right and top perspective view of a nail clipper case showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the nail clipper case in an open state; and,

FIG. 10 is another perspective view thereof showing the nail clipper case in the open state and viewed from another aspect.

The broken lines depict portions of the nail clipper case in which the design is embodied that form no part of the claimed design.
